CRATE

William W. Birnstock, York, Pa., assignor of one-half to Henry H. Snelling, Washington, D. C.

Application October 3, 1929, Serial No. 397,125

6 Claims. (Cl. 217—19)

This invention relates to crates and more particularly to the cross rods for dividing the crate into a plurality of cells or compartments for receiving milk bottles or any other types of bottles and comprises side and end walls, means for securing the walls together, cross rods freely rotatable in said walls and means for securing the cross rods to the walls whereby the same may be quickly and readily detached from the 10 crate, all as more fully hereinafter described and claimed.

An object of the present invention is to provide means whereby the cross rods in a crate may be quickly and readily detached from the 15 walls of the crate so that after the crate has been repaired, it is possible to re-use the cross rods and fastening means.

A further object of the present invention resides in the provision of a member adapted to be 20 inserted in one of the sections forming the wall of a crate for frictionally engaging and positively securing one end of the cross rods. These cross rods which form cells or compartments for receiving bottles are subject to severe strain and 25 wear and by making the same freely movable or rotatable within the walls of the crate considerable strain is taken from the crate itself due to the fact that in withdrawing bottles the side walls strike the cross rods and when adapted to freely rotate an easy withdrawal of the 30 bottle is effected.

The present devices which are now on the market are subject to rather rough treatment and the life of the average milk bottle crate is more 35 or less limited due to the fact that the cross rods now in use are permanently secured or riveted to the walls of the plate. The fact that ice is packed over the milk in these crates causes the crates to become water soaked which in a short 40 course of time rots and decays the wood surrounding the cross rods and makes it impossible to use the crate or the cross rods any great length of time. The present invention overcomes such a difficulty and materially reduces 45 the cost of manufacture and sale price of the crates. The crate to which the present cross rod and fastening means is attached is preferably of the built up type including a plurality of slats of sufficient durability to stand the wear and 50 tear necessary and which are held together by interlocking corner angles.

The cross rods are passed thru openings in the slats and are of a smaller diameter than the opening in the slats thereby allowing for a freely 55 revolvable movement of the cross rods forming

the individual compartments or cells. One end of the cross rod may, if desired, be provided with an enlarged head for retaining the cross rods in the slats while the opposite end is adapted to be inserted into stud or rivet which is positioned thru a like opening in the opposite slat, and by tapping the stud so as to bring it adjacent the outside wall of the slat, the stud may receive within its bore the free end of the cross rod, which is locked in the stud by frictional engagement. Should one of the particular slats in the crate become defective it is only necessary to remove that particular slat, prior to which, the cross rod is readily removed by placing a punch in the bore of the stud and by a slight force applied thereto, the cross rod is quickly detached from the slat.

A still further object of the present invention is to provide a locking stud for the cross rods which will securely retain the cross rods in position and which may be easily withdrawn from the crate after the cross rods have been detached thereby allowing re-use of the studs as well as the cross rods.

Further objects will become apparent as the 60 description proceeds and as set forth in the appended claims.

In the drawing:—

Figure 1 is a perspective view of a crate consisting of a plurality of slats secured by interlocking corner angles and showing the cross rods passing thru certain slats.

Figure 2 is a transverse section thru the crate showing the stud securing the cross rods.

Figure 3 is a detailed perspective view of the 90 locking stud.

Figure 4 is a transverse section thru the crate showing locking studs secured to both ends of the cross rod.

Figure 5 is a transverse section thru the crate showing another form of locking stud adapted to engage an annular groove formed in the cross rod.

Figure 6 is a perspective view of the stud shown in Figure 5.

Referring more particularly to the drawing 10 represents the crate in its entirety. This crate 100 consists of a number of selected hard maple end and side slats 11 superimposed upon each other and secured together by means of the interlocking corner angles 12 and 13. The cross rods 14 105 are of substantially heavy wire and are adapted to divide the crate into a plurality of cells or compartments for receiving milk bottles and the like. Certain of the slats 11 are provided with openings 15, each of the openings receiving the 110

cross rod 14 which may have, if desired, an enlarged head 16 fitting within the countersunk portion 17 of the outer face of the slat 11. The cross rods 14 extend to the opposite side of the crate and in a similar opening 15 there is positioned locking studs 18 each of which is provided with an enlarged head 19 adapted to be positioned within the countersunk portion 20 on the outer face of the slat. A free end of the cross rod 14 is received within the bore 21 of the locking stud 18 and is frictionally held thereon so as to prevent the cross rod 14 from being disengaged from the locking stud except when it is necessary to remove the same from the particular slat thru which it passes when it is desired to replace that slat within the crate.

While I may provide the cross rods 14 with integral heads obviously this is not necessary and I may use commercial circular rod stock merely cut to length and provide two heads each detachable as in Figure 4. In this case the studs 18^a are very slightly tapered and are jammed on to the cross rods 14^a. In this construction the rods of course will revolve as before and the diameter of the sleeve 22^a as in one form of the invention will be smaller than the lesser diameter bore 15 and the head 19^a will snugly engage the circular larger diameter bore 17.

The openings 15 formed in the slats for receiving the cross rods 14 and the locking studs 18 are of a diameter greater than the diameter of the extension 22 of the locking stud which receives the free end of the cross rod 14 and the diameter of the cross rod. By providing these openings of a greater diameter than that of the locking bolt and cross rod the cross rods are allowed to freely rotate in the slats which relieves the slats from any strain due to the withdrawal of a bottle from any one of the cells. The present constructions now in use provide cells or compartments of a width just sufficient to allow a bottle to be inserted or withdrawn, and when the bottle is inserted the cross rods frictionally engage the periphery of the bottle to retain the same within the cell and oftentimes bottles having letters embossed thereon cannot be easily withdrawn from the cells because there is a wedging action between the embossed letters and the cross rods due to the fact that the cross rods are rigidly secured within the crate by rivets or the like and are not capable of a free or rotatable movement within the same. By permitting the cross rods forming the individual cells of the crate to revolve freely within the slats, it is possible to readily withdraw a bottle whether having embossed letters thereon or not, due to the fact that as the bottle is being withdrawn from the cell and should come into contact with the cross rods it may be readily withdrawn as the cross rods are adapted to freely rotate thereby eliminating any friction between the cross rods and the bottle and therefore the usual strain on the crate.

An important feature of my invention lies in having the rods rotatable and I wish it distinctly understood that my invention contemplates the provision of rotatable rods of any form whatsoever either in the preferred form or with two replaceable studs 18^a or even if the heads be made integral with the rods. In practice I find that every advantage is present when I have one head integral with the rod and have the headed sleeve stud such as shown, this stud in practice being made of a high carbon special analysis steel while

the rod itself is made of the usual stock and the head is upset as in nail making.

As regards the showing in Figure 5, the slats 11 are provided with the openings 15 for receiving the cross rod and locking stud. In this construction, the cross rod is provided with an annular groove 23 at a point near its end for receiving the depressed annular rib 24 formed in the locking studs 18 which are provided with the enlarged head 19 adapted to be positioned within the countersunk portion 20 on the outer face of the slats. This locking stud is preferably made of spring steel and is provided with a central bore to receive the ends of the cross rods while it is split longitudinally as at 25 to allow for expansion and contraction of the stud when applying the cross rods thereto. The opening 15 in the slats is likewise of a larger diameter than the diameter of the sleeve so as to allow free rotation of the cross rods within the crate and also allow for the expansion of the locking stud 18 when engaging the cross rods until the annular depressed rib 24 fits into the corresponding annular groove 23 on the cross rods. The interfitting of the rib and groove securely retains the cross rods in position within the crate until such time as it is necessary to detach the cross rods from the crate to substitute a new slat for the worn out one.

It is a general practice when milk bottles are positioned in the crate to pack ice around the bottles to keep the milk cold until delivered. This soon causes the respective slats to become water soaked and eventually to rot and decay but under the present invention it is possible to remove the particular slat or slats that may have decayed and to replace them with new ones. It is also possible to re-use the cross rods indefinitely and this is accomplished by the fact that the cross rods are freely rotatable within the slats and are frictionally held therein by the locking stud. It is only necessary to apply a punch within the bore of the locking stud and give it a slight impulse from a hammer or other device which will result in the cross rod 14 being withdrawn from the locking stud and readily adaptable to be withdrawn from the opposite side of the other slat.

What I claim is:

1. A crate consisting of a plurality of independently removable slats forming side and end walls, independently removable cross rods extending into opposite slats to form cells, one end of each rod being substantially cylindrical and solid but having an annular groove therein, and securing means each having a cylindrical bore entirely therethrough substantially of the diameter of the rod and having in said bore an annular depressed rib for frictionally engaging the annular groove near the end of the rod, said bore exposing to view the end of the rod and permitting the use of a drift pin the diameter of the rod for removing any chosen rod from the crate by driving the rod out of the securing means from the outside of the crate and without disturbing the other rods.

2. The device of claim 1 in which the securing means consists of a spring metal stud having a longitudinal slot therein.

3. A crate consisting of a plurality of independently removable slats forming side and end walls, independently removable cross rods extending into opposite slats to form cells, one end of each rod being substantially cylindrical and solid, and securing means each having a cylindrical bore entirely therethrough substantially of the diameter of the rod for frictionally engaging the free

end of a rod, said bore exposing to view the end of the rod and permitting the use of a drift pin the diameter of the rod for removing any chosen rod from the crate by driving the rod out of the 5 securing means from the outside of the crate, and without disturbing the other rods.

4. A crate consisting of a plurality of independently removable slats forming side and end walls, independently removable cross rods extending into opposite slats to form cells, one end of each rod being substantially cylindrical and solid, and securing means each consisting of a head and a hollow, unbroken, cylindrical sleeve, said sleeve frictionally engaging the rod but free of the slat, permitting easy removal of the rod, said slats having bores therein of greater diameter than the outside diameter of the sleeves to provide such freedom of the sleeve.

5. A crate consisting of a plurality of independently removable slats forming side and end walls, independently removable cross rods extending into opposite slats to form cells, one end of each rod being substantially cylindrical and solid, and securing means each consisting of a head and an integral hollow, unbroken, cylindrical sleeve, said head fitting snugly a slat while the sleeve frictionally engages the rod but is free of

the slat, permitting easy removal of the rod, said slats having bores therein of greater diameter than the outside diameter of the sleeves to provide such freedom of the sleeve.

6. A crate consisting of a plurality of independently removable slats forming side and end walls, independently removable cross rods extending into opposite slats to form cells, one end of each rod being substantially cylindrical and solid, and securing means each having a cylindrical bore entirely therethrough substantially of the diameter of the rod for frictionally engaging the free end of a rod, said bore exposing to view the end of the rod and permitting the use of a drift pin the diameter of the rod for removing any chosen rod from the crate by driving the rod out of the securing means from the outside of the crate, and each securing means consisting of a head and an integral hollow, unbroken, cylindrical sleeve, said head fitting snugly against a slat while the sleeve frictionally engages the rod but is free of the slat, permitting easy removal of the rod, said slats having bores therein of greater diameter than the outside diameter of the sleeves to provide such freedom of the sleeve. 100
